Inventor:
Julius A. Barninghams,
by Wright Wagner Atty.

UNITED STATES PATENT OFFICE.

JULIUS A. BERNINGHAUS, OF ST. LOUIS, MISSOURI.

ELECTRIC HEATER.

Application filed January 21, 1922. Serial No. 530,764.

To all whom it may concern:

Be it known that I, JULIUS A. BERNINGHAUS, a citizen of the United States, residing at the city of St. Louis, in the State of Missouri, have invented certain new and useful Improvements in Electric Heaters, of which the following is a specification.

This invention has for its object to provide an electrical heater that will more quickly heat the air in a room and which can be directed so as to reach cold spots or to produce a general circulation in the quickest time. This heater is also adapted to be regulated so that its efficiency can be increased or reduced according to need by means of turning on or off an electric motor in conjunction therewith.

In the accompanying drawings forming part of this specification, in which like numbers of reference denote like parts wherever they occur,

Figure 1 is a side elevation; and

Figure 2 is a side elevation taken at a right angle to Figure 1.

The base 1 contains grooves or depressions 2 adapted to receive lugs 3 by which motor 4 is attached to base 1 by means of screws 5. Motor 4 is mounted well within the circumference of base 1 and helps to weight the same and to keep the entire device compact. It is mounted as near as possible to central standard 6 and well within the circumference 7 of base 1.

A fan 8 having blades 9 is mounted on base 1 and the shaft 10 of motor 4 adapted to rotate the blades 9. Holes 11 in the housing of fan 8 permit the suction of air into pipe 12, by which the air is conducted into the encircling chamber 13 formed on or in connection with the radiator 14, there being a plurality of holes 15 acting as passages from the interior of chamber 13 to the space within the basin of radiator 14.

When the air forced through pipe 12 into chamber 13 strikes the wall of basin or radiator 14, the said material acts like a baffle to cause the air to travel in two directions, as indicated by the arrows in Figure 2. Furthering this object, the holes 15 nearest the mouth or exit 16 from pipe 12 are smaller in diameter than the holes 15 found further away from the said mouth 16, and it is the intention that the same shall preferably graduate in size. Thus it will result that the air emitted through pipe 12 will find its way all the way around chamber

13 and thus all become heated by means of the coil 17 of resistance wire, whereas if the holes near mouth 16 were as large as those further away therefrom, such air would not have time to become heated and the efficiency of the heater would be relatively much diminished thereby.

By the radiator 14 being directed upward, as shown in Figure 1, a tendency is at once created to force the warm air upwardly, while the suction through holes 11 tends to draw the cold air from the bottom of the room or the floor, this combined action tending immediately to set up a current of warm air rising toward the ceiling, and of cold air descending toward the floor, whereby the temperature of all parts of the room is most quickly equalized.

The radiator 14 is pivoted at 18 to central standard 16, and if pipe 12 be made telescoping or of flexible material or of extensible members, the direction of tilt of radiator 14 can be changed at will, so as to direct the hot air in various directions.

The wire 19 conducts the electric current to the coil 17 and causes the same to evolve heat whether or not motor 4 and fan 8 be in operation. If the heat thus secured be not sufficient, however, motor 4 can be turned on by means of switch 20, which will immediately result in the operation of fan 8 and the more rapid heating and distribution of the hot air. When fan 8 is not in operation there is no forcing of the heated air out of the radiator 14, just as there is no forced in-draft or suction of air to be heated. The motor 4 is fed by branch wires 21.

Having thus described this invention, I hereby reserve the benefit of all changes in form, arrangement, order, or use of parts, as it is evident that many minor changes may be made therein without departing from the spirit of this invention or the scope of the following claims.

I claim:

1. In an electric heater the combination of a radiator having holes, an air chamber in connection therewith, an air pipe leading to the said chamber, and a fan.
2. In an electric heater the combination of a radiator having holes, an air chamber in connection therewith, an air pipe leading to the said chamber, a fan, and a motor.
3. In an electric heater the combination of a radiator having holes, an air chamber in connection therewith, an air pipe leading

to the said chamber, a fan, a motor, and a switch.

4. In an electric heater the combination of a radiator, a coil, an air chamber, a pipe leading thereto, air passages between the said chamber and the said radiator, electric connections for the said coil, a fan in connection with the said pipe, a motor whereby the said fan is operated, and branch electric connections for the said motor.

5. In an electric heater the combination of a radiator, a coil, an air chamber, a pipe leading thereto, air passages between the said chamber and the said radiator, electric connections for the said coil, a fan in connection with the said pipe, a motor where-

by the said fan is operated, electric connections for the said motor, and a switch, whereby the said motor and fan may be rendered inoperative without affecting the said coil.

6. An electric heater comprising a radiator having holes, an air chamber communicating with the said radiator through the said holes, an air pipe leading to the said air chamber, a fan communicating with the said pipe, and means for operating the said fan, the said holes being of less diameter near the said pipe than further away.

In testimony whereof I hereunto affix my signature.

JULIUS A. BERNINGHAUS.
